UNITED STATES PATENT OFFICE.

GOODRICH Q. LEWIS, OF WHEATON, ILLINOIS, ASSIGNOR TO WILLIAM H. MINER, OF CHAZY, NEW YORK.

RAILWAY-CAR DRAFT-RIGGING.

1,300,421.

Specification of Letters Patent. Patented Apr. 15, 1919.

Application filed May 24, 1916. Serial No. 99,486.

To all whom it may concern:

Be it known that I, GOODRICH Q. LEWIS, a citizen of the United States, residing at Wheaton, in the county of Du Page and 5 State of Illinois, have invented a certain new and useful Improvement in Railway-Car Draft-Rigging, of which the following is a full, clear, concise, and exact description, reference being had to the accompanying 10 drawings, forming a part of this specification.

This invention relates to improvements in railway car draft rigging.

One object of the invention is to provide 15 a draft rigging of high capacity of the tandem type so arranged that the shock absorbing units may be inserted and removed without disturbing the yoke and draw bar.

Another object of the invention is to provide 20 a draft rigging of the tandem type wherein is employed a horizontal yoke arranged to remain stationary under buff and having upper and lower, front and intermediate stops extending between the sills and 25 bracing the latter.

The invention furthermore consists in the 30 improvements in the parts and devices and in the novel combinations of the parts and devices herein shown, described and forming the subject matter of claims.

In the drawing forming a part of this specification, Figure 1 is a vertical longitudinal sectional view of a draft rigging embodying my improvements. Fig. 2 is a horizontal sectional view of the structure illustrated in Fig. 1 and taken on the line 2—2 thereon. Fig. 3 is a vertical, transverse sectional view taken substantially on the line 3—3 of Fig. 1. And Figs. 4, 5 and 6 are 35 perspective views of the front follower, the front intermediate follower, and the transmission block respectively employed in my construction.

In said drawings, 10—10 denote channel 40 center sills or draft members spaced the usual distance apart and between which extend horizontal front, upper and lower stops 11 and 12; intermediate upper and lower stops 13 and 14; and a rear abutment or stop 45 casting 15. Each of the stops 11 and 12 has a horizontally extending main web and vertical side flanges, the latter being suitably riveted to the sills 10. Each of said stops is further provided, at its rear end, with a 55 vertical flange 16 to form a stop shoulder

or abutment for the front follower 17 of the draft rigging to abut against. Each of the intermediate stops 13 and 14 is substantially U-shape in vertical section as clearly illustrated in Fig. 1 and is provided further 60 with forwardly and rearwardly extended flanges 18—18 riveted to the sills and additional strengthening tapered horizontal flanges 19—19. The rear stop or abutment block 15 is provided with a vertical front 65 face 20 for the rear end of the yoke 21 to abut against and with side webs 22—22 riveted to the sills, the front wall 20 being suitably braced by a plurality of horizontally extending webs 23—23. The yoke 21 70 is arranged horizontally and is guided between the sets of front and intermediate stops, as clearly appears from the drawing. At their front ends, the arms of the yoke are provided with elongated slots 24 to receive 75 the coupler key 25 by which the yoke is connected to the draw bar 26, said key also extending through elongated slots in the sills.

Each of the shock absorbing units, which are arranged in tandem, preferably comprises sets of twin arranged springs 27—27 and followers therefor. The front shock absorbing unit has the front follower 17 and the front intermediate follower 28, the 80 latter being shown more in detail in Fig. 5. As there shown, the follower 28 is recessed at its center as indicated at 29 to thereby permit the rear end of a column 30 formed on the front follower 17, to slide 85 therethrough. The column 30 is concaved on both its upper and lower surface to thereby form suitable seats for the twin arranged springs 27—27. The column 30, as clearly appears from Fig. 4 is larger at its 90 front portion as indicated at 31, thereby forming shoulders 32—32 adapted to engage the front intermediate follower 28 at the end of the buffing and draft movements and thus limit the compression of the springs. 100 It will also be noted that each of the followers 17 and 28 is provided with suitable bosses 33 on which the springs 27 are mounted.

The rear shock absorbing unit comprises 105 a front intermediate follower 34 and a rear follower 35 and twin arranged springs 27—27, the latter being suitably separated by a combined spring spacer and limiting block 36. The two sets of springs and followers 110

are held in proper position by detachable saddle plates 37 bolted to the lower flanges of the sills, the bolts being locked by clips 38.

In order to operate the gear as a tandem gear under draft, the yoke 21 is provided at its center with inwardly extending lugs 39-39, each having a front shoulder 40 adapted to engage the rear face of the follower 28 and pull the latter forwardly under draft. To actuate the rear unit under buffering, a floating pressure transmitting block 41 (see Fig. 6) is provided which fits between the intermediate followers 28 and 34 and is engaged by the rear end of the column 30. The lugs 39 are beveled rearwardly and outwardly as indicated at 42 and the sides 43 of the block 41 are correspondingly beveled, as appears from Fig. 2.

In assembling the device, the yoke is slipped in endwise, after which the block 41 is placed in position between the intermediate stops 13 and 14. The shock absorbing units may then be inserted from below, as is apparent and the draw bar finally inserted and connected to the yoke. The draft gear thus presented is of high capacity in that it comprises tandem arranged twin sets of springs, the parts may be readily assembled and disassembled, the stops are so formed and located as to present the maximum resistance to the strains imposed thereon; and the stops are also relatively small and brace the sills.

I claim:

- 35 1. In a draft rigging, the combination with draft members, of upper and lower, horizontal front and intermediate stops, a rear stop, a horizontal tandem yoke between said upper and lower stops, the yoke remaining stationary under buff, tandem arranged shock absorbing units, insertible and removable from below, within the yoke, said yoke actuating both units in draft, and means for actuating both units in buff.
- 45 2. In a draft rigging, the combination with draft members, of upper and lower, horizontally extending front and intermediate stops, a rear stop casting extending between and secured to the sills, a horizontal yoke abutting at its rear end said rear stop casting, tandem arranged shock absorbing units mounted within the arms of said yoke and between the front and intermediate, and intermediate and rear stops, said yoke actuating both units in draft, and means for actuating both units in buff.
- 55 3. In a draft rigging, the combination

with draft members and tandem arranged stops, of a front follower, front intermediate follower, rear intermediate follower, rear follower, cushioning means between the sets of followers, a yoke having operative engagement with the front intermediate follower to actuate the latter under draft, said yoke remaining stationary under buff, a column extending from the front follower rearwardly, and a block interposed between the intermediate followers, said block being actuated by said column under buff to thereby move the rear intermediate follower rearwardly.

4. In a draft rigging, the combination with draft members and tandem arranged stops, of a horizontal yoke, front, front intermediate, rear intermediate, and rear followers, cushioning means between the sets of followers, a floating block interposed between the intermediate followers, and means for actuating said block from the front follower under buff to thereby compress the rear cushioning unit, said yoke having shoulders arranged to engage the front intermediate follower under draft.

5. In a draft rigging, the combination with draft members, upper and lower horizontally extending front stops, upper and lower intermediate stops, and a rear stop, of a horizontal yoke slidably mounted between the front and intermediate stops, said yoke remaining stationary under buff, tandem arranged shock absorbing units insertible and removable from below while the yoke is in position, said yoke having inwardly extended shoulders arranged to engage the front intermediate follower under draft to thereby move said follower forwardly, and means for operating both units in buff.

6. In a draft rigging, the combination with draft members, upper and lower horizontally extending front stops, upper and lower horizontally extending intermediate stops, and a rear stop, of tandem arranged shock absorbing units, a horizontal yoke, guided between said upper and lower stops and prevented from rearward movement by the rear stop, said yoke having shoulders engaging the front intermediate follower under draft, and means for actuating the rear shock absorbing unit from the front follower under buff.

In witness that I claim the foregoing I have hereunto subscribed my name this 12th day of May, 1916.

GOODRICH Q. LEWIS.
